Attorney.

UNITED STATES PATENT OFFICE.

WALTER H. WILKENING, OF CINCINNATI, OHIO, ASSIGNOR OF ONE-HALF TO CHARLES J. HEILEMAN, OF COVINGTON, KENTUCKY.

LAPEL-BUTTON FASTENER.

1,282,509.

Specification of Letters Patent. Patented Oct. 22, 1918.

Application filed June 2, 1917. Serial No. 172,550.

To all whom it may concern:

Be it known that I, WALTER H. WILKENING, a citizen of the United States of America, and a resident of Cincinnati, in the county of Hamilton and State of Ohio, have invented a certain new and useful Improvement in Lapel-Button Fasteners, of which the following is a specification.

This invention relates to lapel-buttons, or, 10 more particularly speaking, to fastening devices for such buttons.

The object of the invention is to provide fastening means that will enable the button to be easily and safely snapped into place, 15 as well as to be readily removed therefrom.

The details of structure of the fastening device will be fully hereinafter described in connection with the accompanying sheet of drawings, in which latter, Figure 1 is an 20 elevation of the button, showing its fastening device in cross-section and as applied to the fragment of a garment, such fragment being in cross-section and broken off at its opposite ends; Fig. 2, a cross-section of the 25 fastening device, apart from the button; Fig. 3, a cross-section of the outer member of said fastening device, it being the one used to snap the button into place and omitting the anchoring portion of the fastener; Fig. 4, a plan view showing the outer face 30 of the member shown in Fig. 3; Fig. 5, a plan view of the inner face of the anchoring part of the fastener, but showing the blank from which said anchoring portion is made, 35 ready for turning up the anchoring-points; and Fig. 6, a plan view of the blank seen in Fig. 5 but of the opposite side thereof, and showing the said anchoring-points in their upturned position.

40 1 indicates the fragment of goods containing the buttonhole in which the device herein is to be placed for display.

2 indicates the button proper, being preferably a flat one and having a rearwardly-extending, central, threaded shank or stem 45 3, the latter extending through the button-hole in the goods 1.

The device for fastening the button 2 in place on the goods 1 is composed of but two 50 members, an outer one 4 and an inner one 5, the latter forming an anchoring-member that does not turn or rotate but forms a bearing around which the member 4 may

freely rotate when it is desired to remove the fastening device from securing-connection 55 with the button.

The inner disk 5 of the fastening-member is preferably somewhat dished on its inner face that lies adjacent the lapel when in use and it has a central orifice that is slightly 60 larger in diameter than that of the threaded shank 3, a plain shallow flange or hub extension 6 being provided on the opposite side of this disk and adapted to form a ready guide for the free outward passage of the 65 threaded shank 3 in snapping or like ready pushing forward of the fastening-member on such shank for use.

A series of teeth 7 extends or is bent forwardly and from the inner dished face of 70 the disk 5 for anchoring-engagement with the goods of the lapel 1, when the button is in use, as shown in Fig. 1. These teeth 7 are made in the edge of a circular disk, as shown in the blank in Fig. 5 and then turned 75 or bent forwardly or upwardly from the dished face of said disk as shown in Fig. 6, the slits 8 being made in the edge of the blank, as shown in Fig. 5, so that when the teeth are turned upwardly from the edge 80 there will be arc-shape projections 9 left between the teeth. Projections 9 form a bearing on the periphery of the disk 5 that engages under an inwardly-turned flange or bead 10 on the outer disk 4 of the fastening-member, as best shown in Figs. 1 and 2, so that the disk 4 is free to turn around the disk 5 for such purpose as may be desired. 85

The disk 4 is slightly conical to somewhat coincide with the dished disk 5 and it is 90 made of resilient material, T-shape slits 11 being made therein and radiating from a central orifice 12 also made therein, as best shown in Fig. 4, the segments of metal between the T-shape slits being sufficiently resilient to permit them to ride freely over the threaded shank 3 when the fastening-member is snapped or pushed forwardly into place on the inner face of the lapel 1 and with the anchoring-teeth 7 directly imbedded in the goods, whereby the button is securely held in place against accidental removal. The button can thus be instantly snapped into secured position on the lapel 100 when once its shank has been passed through 105 the button-hole usually provided in the goods

- and the fastening-member can be readily released by simply turning the disk 4 backwardly along the threaded-shank 3, the three segmental edges of the central orifice 12 of the disk 4 being adapted to engage the thread of said shank, both in turning the fastening-member from mounted position or place as well as holding it in said mounted position or place.
- 10 The fastening-member is of an extremely simple as well as economical form, it being composed of but two parts that are readily made and put together, and the dished structure of the inner disk 5, together with the plain guide-hub 6, form an extremely convenient means for placing the fastening-member on the threaded shank 3 when the latter is in place in the lapel 1 and ready for fastening.
- 15 20 The disk or member 4 of the fastening device, being the outer one, it is obvious that it is not hidden or out of the way of easy access to the user in the event it becomes out of order and needs attention, and its condition is always open to view as well as to ready repair.

I claim:—

A lapel-button comprising an outer or exposed display-member, an inner or concealed fastening-member, said outer-member having a body-portion or disk with a central, rearwardly projecting screw-threaded shank or stem and said inner fastening-member having a resilient, radially-split disk whose segmentally-orificed center is adapted to engage the said screw-threaded shank for ready snapping into mounted position or detaining place and for reverse-turning from mounted-place along the thread of the said screw-shank, and an internal disk armed 40 with forwardly-bent peripheral anchoring-teeth, and, also, with radial extensions alternating said teeth to each engage beneath an inwardly-turned flange on the said radially-split disk and, also, with a central orifice 45 having a plain outwardly-turned guide flange or hub through which latter the said screw-threaded shank freely passes for detaining-engagement with the segmental edges of the said resiliently-orificed split 50 disk.

WALTER H. WILKENING.
